UNITED STATES PATENT OFFICE.

RICHARD F. BERNDT, OF SAN FRANCISCO, CALIFORNIA, ASSIGNOR TO AUTOMATIC PRINTING DEVICES COMPANY, OF SAN FRANCISCO, CALIFORNIA, A CORPORATION OF CALIFORNIA.

MACHINE FOR PRODUCING RAISED PRINTING.

Application filed May 19, 1924. Serial No. 714,361.

This invention relates to a machine where-
by printed matter may be subjected to a
process of applying a layer of material over
the printed lines, so that the printed char-
5 actors become raised above the plane of the
paper. In this way it is possible, by careful
manipulation, to simulate engraved printing
so closely as to make the product substan-
tially indistinguishable from such work, al-
10 though performed without cut dies and
therefore at relatively small expense. In ad-
dition other embossed effects may be ob-
tained which are impossible in ordinary en-
graving.

15 The process, for its successful operation,
must be used while the printing is still moist
or tacky, and serves to bind the supple-
mentary layer of material until a later step
in the process fuses the material to the print-
20 ing. This material is in the form of a very
finely divided powder, which can be fused
by the application of heat, and thus made
to unite intimately with the printing ink.
For this purpose, resinous material has been
25 found to be very adaptable, since it requires
a heating temperature for fusing that is well
below the dangerous point, and since it may
readily serve as a color carrying medium
that adheres very well to the printed matter.
30 In order that the process be productive of
clean cut characters, free from any blur, it
is necessary to ensure against an excess of
the powder, and for this purpose, the paper
on which the printing appears is vibrated,
35 whereby all of the powder not actually ad-
hering to the printed matter, as shaken off.
The last step in the process is the heating
of the printed matter to fuse the powder,
and then permitting it to cool.

40 Although machinery has been devised in
the past to carry on this process automatic-
ally, yet the character of the product has
not been very high. This I attribute to the
fact that the manipulation of the paper by
45 mechanical elements, such as grippers, cams,
gears, etc., requires the use of many moving
parts near the paper, and consequently some
of the powder as it is sprinkled over the
sheet and shaken off therefrom, can readily

find lodgment in crevices and corners of the 50
moving parts. This deposited powder may
at least partly return to the sheet later on,
and may cause either blurred characters, or
small spots on the paper, or both. It is one
of the objects of my invention to guard 55
against the unnecessary deposition of pow-
der, and consequently the possibility of pro-
ducing an inferior finished product.

In order to secure this object, I arrange
the mechanism in such a way that a separate 60
and distinct portion thereof serves as the
powderer, which after it performs this func-
tion, remains at a comparatively remote dis-
tance from the powdered sheet in the course
of its travel through the machine. Another 65
feature assisting this general result, resides
in the arrangement of the mechanism where-
by a great portion of it is shielded from the
powder as it is sprinkled on the sheet.

It is another object of my invention to 70
improve such processing machines in gen-
eral, whereby they are more reliable in serv-
ice and simple in operation.

It is still another object of my invention
to provide a novel form of powdering de- 75
vice, in the form of a rotary element which
carries the sheet to be powdered, as well as
a scoop or the like for dumping the powder
on the sheet while it is held by the powder-
ing mechanism.

It is still another object of my invention
to provide an improved form of sheet vibrat-
ing device, to remove the loose powder.

My invention possesses other advan-
tages features, some of which, with the fore- 85
going, will be set forth at length in the
following description, where I shall outline
in full that form of the invention which I
have selected for illustration in the drawings
accompanying and forming part of the pres- 90
ent specification. Although I have shown in
the drawings but one embodiment of my in-
vention, I do not desire to be limited there-
to, since the invention as expressed in the
claims may be embodied in many other 95
forms also.

Referring to the drawings:

Figure 1 is a side elevation of substan-

5 tially a complete machine embodying my invention, with a portion of the delivery conveyor broken away, as well as a portion of the standards, whereby the size of the figure can be maintained small enough to permit showing the complete machine on a single sheet;

10 Fig. 2 is an elevation of the machine shown in Fig. 1, and taken from the other side of that figure;

15 Fig. 3 is an enlarged detail view, partly in section, of some of the mechanism shown in Fig. 2;

20 Fig. 4 is a top plan view of the complete machine, the delivery conveyor being however partly broken away;

25 Fig. 5 is a detail sectional view of the powdering device, and illustrates in a clear manner how the powder is delivered to the printed sheet;

30 Fig. 6 is a sectional view of the machine shown in Fig. 1;

35 Fig. 7 is a fragmentary sectional view, similar to Fig. 6, but from another direction, whereby other parts of the mechanism are brought to view;

40 Figs. 8, 9 and 10 are diagrammatic views, showing three stages in the progress of the sheet through the machine;

45 Fig. 11 is an enlarged detail view, partly in section, illustrating the mechanism for opening and closing the grippers that carry the sheets from the powdering device and deliver them to the heating device;

50 Fig. 12 is a plan view of the mechanism shown in Fig. 11;

55 Fig. 13 is an enlarged fragmentary plan view of the mechanism used for introducing the sheets into the powdering device; and

60 Fig. 14 is a diagrammatic view illustrating that stage in the progress of the paper through the machine during which it is released from the powdering device and gripped by the grippers to transport it to the shaker and then to the heater.

65 The general appearance of the machine is well disclosed in Fig. 1, in which some of the gear covers and guards have been removed, in order to expose some of the mechanical connections and drives. A suitable stand 21, shown in this instance as a casting, serves as a support for all of the parts of the machine. It may rest directly on the floor, and in that case, it is made high enough to facilitate use by an operator. As a source of motive power for the mechanism, I illustrate a small electric motor 22, which may be of any desired type. This motor is conveniently supported by the table or stand 21, near the bottom thereof. A pair of side frames 23 are bolted or otherwise attached to the top of stand 21, and serve to provide bearing supports and the like for the various elements in the mechanism.

70 The machine is preferably located near

the delivery end of a printing press, so that the printed matter may either be deposited on the receiving conveyor 24 (shown most clearly in the plan view of Fig. 4), automatically by the printing press, or manually. 75 This receiving conveyor is shown in the present instance as supported on a swinging frame 25, which is pivoted near one end on the shaft 26. This shaft is journaled in the side frames 23, and serves in addition as an element in the transmission connecting the motor 22 with the operating mechanism. The frame 25 is held in extended position by the aid of a bifurcated strut 27, the legs of which are detachably connected with any 80 convenient part of the stationary supporting members. By the aid of this construction, the entire conveyor and its associated mechanism may be swung downward at will, for saving space in storage or shipping. A 85 rotatably mounted shaft 28 extends across the receiving conveyor frame 25, near its free end, and a series of flexible loops or belts 29 pass around both shafts 26 and 28. These belts form the travelling conveyor, 90 motion thereto being imparted by the rotation of shaft 26. This shaft is driven as by the aid of a pulley 29' (Fig. 2) and belt 30 from the motor 22. Guides 31 for the edges of the printed matter are supported in any 95 appropriate manner on the frame 25, as by the use of one or more transverse bars 32 connecting the two sides of frame 25. A belt tightener 33 (Fig. 6) may if desired, be provided for the loops 29.

100 A sheet of printing 34 carried forward by the receiving conveyor 24, is indicated diagrammatically in Figs. 5, 8 and 9. The entire conveyor is preferably slanted downwardly so as to facilitate the placing of such sheets thereon. The conveyor deposits the sheet 34 at the end of its travel so that its front edge rests on a stationary plate 35. This plate extends between the side frames 25, and somewhat below the top surface of the conveyor belts 29, as shown most clearly in Figs. 5, 8, 9 and 10. A top fragmentary view of the plate is also clearly shown in Fig. 13. In order to position the sheet 34 properly with respect to the plate 13, so that it may later be operated upon by the powdering device, there are provided several stop fingers 36, against which the edge of the paper 34 is urged as the conveyor moves. The conveyor belts 29 are purposely made from such material that when these fingers are thus engaged, the belts can readily slip with respect to the bottom surface of paper 34, so that they may move although the plate is stationary.

110 The fingers 36 are preferably made from spring material, and are fastened at intervals to a shaft 37, which is capable of being oscillated so as to free the paper when necessary. This shaft extends across the con-

veyor frame 25, and is journaled in brackets 38 carried at each side of this frame. The fingers 36 are resiliently urged to non-engaging position by the aid of tension springs 39 (Fig. 6), one end of which is fixed to a stationary bar 40 and the other end, to an arm 41 fastened to the shaft 37. The upper end of bar 40 also serves as a stop for the arm 41. It is also to be noted that the extremities of fingers 36 are formed with abrupt projections 42, forming surfaces substantially perpendicular to the plane of the paper 34.

The normal position of the fingers 36 is that shown for example in Fig. 6, in which they provide no hindrance for the withdrawal of the sheet 34 by the powdering device mechanism. They are operated only momentarily to position the sheet 34 properly with respect to the plate 35. In order to restrain the sheet 34 until the fingers 36 are moved downwardly by the mechanism associated with the powdering device, I provide a set of fingers 43 (Figs. 6 and 13), which normally extend upwardly between the belts 29 and slightly in advance of the fingers 36. These fingers stop the sheet 34 until such time as the spring fingers 36 are moved downwardly into engagement with the plate 35. For this purpose these fingers 43 are fastened to a shaft 44 extending between the top and bottom reaches of the belts 29, and urged to engaging position by the aid of a tension spring 45 acting on an arm 46 and anchored at one end to the stationary bar 40. The free end of arm 46 projects underneath the arm 41 that operates the fingers 36, as shown most clearly in Fig. 13. By this arrangement it is assured that upon rotation of shaft 44 in a counterclockwise direction (Fig. 6), the fingers 43 will first be withdrawn from above the conveyor belts 29, which action permits the paper 34 to move farther toward the fingers 36; then on continued rotation, arm 46 will engage arm 41 and thus cause counterclockwise rotation of shaft 37 and consequent movement of fingers 36 to engaging position. The proportions of the elements can be arranged in such a way that the projections 42 of fingers 36 are placed in the path of the paper before it reaches the plate 35.

The operation of shaft 44 is accomplished automatically by the mechanism associated with the powdering device. For this purpose, the shaft 44 is provided with an arm 47 (Figs. 6 and 13), which is adapted to be moved downwardly and to rotate the shaft 44 against the resilient force of spring 45. This arm is arranged to be engaged by a projection or cam 48 (Figs. 4, 6 and 13). This cam is in this instance shown as a thin curved blade supported at one side of a structure rotating with the shaft 49 and located between the two side frames 23. This

structure will be described in connection with the powdering device; for the present it is sufficient to note that cam 48 is for each revolution of shaft 49, caused to depress arm 47 for a brief period, sufficient to bring the sheet on the plate 35 in proper position to be grasped by mechanism associated with the powdering device. The drive for shaft 49 is accomplished, as shown most clearly in Fig. 1, from shaft 26 that also drives the receiving conveyor belts 29. The mechanical connections between shafts 26 and 49 include a sprocket wheel 50 fastened to shaft 26 and located on the outside of one of the frames 23, and a sprocket chain 51 driven by the wheel 50, and passing over a sprocket wheel 52, as well as other wheels 53 and 54. The wheel 52 is fastened to a shaft 55 having a bearing in side frame 23, and this shaft carries a gear wheel 56 meshing with the gear 57 that is fastened to the shaft 49.

One of the important features of my invention resides in the manner in which the powdering device operates. In prior machines, grippers are used to lead the sheet of printing past a hopper or the like, then to some form of remover for the unattached powder, and finally to the heater. In such machines it is difficult if not impossible to free all of the loose powder from the operating mechanism, and some of the powder finds its way back to the paper. With my invention this is entirely prevented, since the paper is fed to the powdering mechanism and delivered therefrom to another mechanism having no direct connection therewith. A large part of the powdering mechanism is supported on a frame 58, preferably cast. This support consists of a pair of sides, each having two arms 59 and 60, the pair of sides being connected by a strap 61. (Figs. 6 and 7.) One of the arms 59 carries the cam 48 heretofore referred to.

The frame 58, as it revolves with rotation of shaft 49, causes a powder holder or scoop 62 first to become loaded, and then to spill its load of powder over the sheet 34, whence all unused powder may fall back into the storage receptacle in which the scoop 62 operates. In the present instance a shallow sheet metal trough 63 is provided as a receptacle for a comparatively small mass of the fusible powder 64. This trough extends entirely across between the two side frames 23, and projects forwardly underneath the plate 35. In the other direction, a steep wall 65 is formed as a continuation of the trough side, so that as mechanism later to be described carries the paper or sheet away from the powdering device and along this wall, the unattached powder may readily find its way back into the trough. It is furthermore to be noted that a comparatively small amount of powder is utilized in the machine; in this way, there is

greater assurance that none can find its way to undesired localities, and also that no great excess of powder is poured over the sheet, whereby there is freedom from blurring of the lines.

The construction and operation of the powdering mechanism will now be described in detail. One result of the rotation of shaft 49 is the temporary depression of arm 47 by cam 48, and consequent placing of the sheet over the plate 35. While on this plate, the sheet is gripped between a clamping bar 66 extending across to the arms 59 of frame 58, and a plurality of spring 10 gripper fingers 67. This clamping action is best illustrated in Figs. 5 and 9. The fingers 67 are in the disengaging position of Fig. 8 until just after the fingers 36 are brought to disengaging position, due to the 15 passage of the cam 48 from off the arm 47. At that point in the operation, the clamping bar 66 is disposed over the rear edge of plate 35, there being slots 68 (Figs. 4 and 7) which permit it to move over the fingers 20 36, and in which these fingers are accommodated. Thus the clamping edges 69 are positioned over the sheet 34, and the gripping fingers 67 are brought into engagement with these edges, in a manner to be described 25 hereinafter. In order to permit this clamping movement, the plate 35 is provided with a series of slots 70 (Fig. 13) alined with the fingers 67, whereby these fingers may dovetail between the fingers 36 during their 30 clamping movement.

The manner in which these fingers are operated may be best described in connection with Figs. 5 and 7. A rotatable shaft 71 extends between the sides of frame 58 and 35 carries the fingers 67. To the shaft at one end is connected an arm 72, and a tension spring 73 is fastened at one end to the extremity of the arm, and at the other, anchored to a stationary part of the mechanism. This spring, in the position of Fig. 5, serves to provide a resilient clamping force, but if shaft 71 be rotated far enough in a clockwise direction, the arm 72 will carry the spring to the other side of the 40 shaft 71, which will then snap it over center to the open position of Fig. 7. The rocking of the shaft in the reverse direction will cause the engagement of the spring fingers 67 with the clamping bar 66.

The movement of the shaft 71 is properly 45 timed with respect to the rotation of the main shaft 49, so as to perform its clamping and releasing functions, respectively when the parts are in proper position to receive the sheet 34, and when in proper position to deliver it to the succeeding mechanism. To accomplish this result, a lever 50 55 having a pair of forked ends is attached to one end of shaft 71, and near one of the side frames 23. The forks are arranged to

coact with stationary pins or projections 75 and 76 appropriately fastened to the frame 23, as the powdering mechanism rotates with shaft 49. Thus in Fig. 7, as the shaft 49 rotates in the direction of the 70 arrow, carrying with it the frame 58 and shaft 71, one of the forks of lever 74 will engage pin 75 at a definite point of its travel. The pin 75 will urge the lever 71 to rotate in a clockwise direction, and will 75 ultimately cause the spring 73 to snap the fingers 67 into clamping position. Of course the pin 75 is located in such position that this takes place just as the fingers 36 are released from plate 35, by the movement 80 of cam 48 off of arm 47. Continued rotation of shaft 49 through part of a revolution will ultimately bring the other forked end of the lever 74 into coaction with the other pin 76, and the shaft 71 will be rotated to releasing position. Of course other devices in place of the forked lever 74 and pins 75 and 76 could be substituted for effecting rotation of shaft 71, but it is unnecessary to detail such obvious modifications.

While the sheet is gripped by the mechanism just described, during a period corresponding to an angular movement of shaft 49 of almost 180° in this instance, as determined by the spacing of pins 75 and 76, the sheet is subjected to a powdering operation. This is accomplished by the aid of scoop 62, which extends between the arms 60 of frame 58 and is rigidly fastened on shaft 77 by the 100 aid of lugs 78 formed on the bottom thereof (Figs. 4 and 5). This shaft 77 is rotatably supported in arms 60 of the frames 58. The mechanism is so arranged that this scoop 62 is made to dip into the powder 64, and to 105 dump it in a guide or trough 79, in response to the proper degree of rotation of shaft 49. The scoop 62 has a lip 87 at each side of which there are attached prongs 88. These prongs converge toward the lip and are wide 110 enough at their free end to extend substantially entirely across the powder trough 63; in this way the prongs act as guides for the powder, substantially all of which finds its way into the scoop 62. The dumping is accomplished immediately after the sheet 34 is withdrawn from the plate 35, this condition being disclosed in Fig. 5.

The mechanism provided for manipulating the scoop 62 for scooping and dumping the powder is best disclosed in Fig. 6. An operating arm 80 is connected to the shaft 77 that carries the scoop 62, and it is evident that by rocking this arm to the desired degree as the scoop revolves about the axis of main shaft 49, this scoop may be caused to dip into the powder 64 and later to dump its acquired load. In order to move the arm in this manner, any appropriate mechanism such as a stationary grooved cam 81 may be 115 120 125 130

provided. This cam, as shown most clearly in Figs. 4 and 13, is shown as appropriately supported on the inside of one of the frames 23. A groove 82 is cut in the cam, which accommodates a pin or roller 83 carried near the end of arm 80 and having an axis parallel to that of the scoop shaft 77. It is evident that by properly forming the groove 82 especially at that place where it controls movement of the scoop 62 into the powder trough 63, it is possible to cause this scoop to reach down into this trough and practically to the bottom thereof, to dip out nearly all of the powder 64. Continued movement 15 of pin 83 in the groove 82 will ultimately bring the scoop 62 to the position of Fig. 5, where it is shown as depositing the powder onto the bottom of the trough or guide 79. This trough is in the present instance shown 20 as pivotally supported near one edge on the scoop shaft 77, by the aid of the side pieces 84 (Fig. 4). Its movement around this shaft is also controlled by the cam 81, so as to bring its free edge or lip 86 down close to the front edge of the sheet clamping bar 66 25 and over the sheet 34. Thus just prior to the dumping of scoop 62, as shown in Fig. 9, this trough 79 is raised a little above the bar 66 so as not to interfere with the operation 30 of any of the mechanism or with the withdrawal of the sheet 34 from plate 35.

The movement of trough 79 to the operative position of Fig. 5 is accomplished in this instance by the aid of certain levers and links, shown most clearly in Figs. 6 and 7. A bracket 85 is attached to one of the arms 59, and a shaft 89 is pivoted therein. This shaft carries a crank arm 90, connected as by a link 91 to the bottom of the trough 79 and near its lip end. In order to rock the shaft 89 and thus operate the arm 90 and link 91 to move the trough, I provide an arm 92 attached to the shaft 89 and carrying a pin or roller 93 coacting with the cam groove 82. That portion of the groove which coacts with the pin 93 just after the sheet 34 is gripped by the fingers 67 is so formed that the toggle formed by arm 90 and link 91 is brought nearer to a straightened condition, and the trough 79 is correspondingly positioned over and close to the sheet 34. It is to be noted that the trough serves as a shield for the clamping mechanism as well as for other parts of the mechanism, and no powder can fall thereon. Although the powder is deposited near the engaged edge of sheet 34, yet as this sheet is carried around by the frame 58 to the releasing position of Fig. 14, the powder slides over the sheet and some returns back into the trough 63. Whatever loose powder stays on the sheet is afterwards removed in a manner to be described. However, the wet or sticky printing retains sufficient powder for producing the desired raised effect.

After the shaft 49 rotates to a position to bring the sheet 34 to the position of Fig. 14, it is released by the mechanism described hereinbefore, and delivered to another set of grippers 94 which serve to carry the sheet 70 to the shaker and then to the heater. The grippers 94 and their opening and closing mechanism are most clearly illustrated in Figs. 11 and 12. Five grippers are shown in this instance, disposed in spaced relation 75 across the space between the side frames 23. They each include a pair of spring fingers, fastened respectively to an upper shaft 95 and a lower shaft 96. These shafts are rotatably supported in a pair of brackets 97, whereby by rotation of these shafts the grippers can be made to open and close. The brackets 97 are rigidly fastened to a shaft 98 that extends across the machine, and is moved to carry the entire row of grippers 80 to various operating points, as will be described hereinafter. 85

In order to urge the spring grippers 94 resiliently together, I provide a pair of short crank arms 99 fastened near one end of the shafts 95 and 96, and a pair of long crank arms 100 at the other end of the shafts; a spring 101 tending to pull the arms together is provided for each set. In this way, the shafts 95 and 96 are resiliently urged in such directions as to keep the grippers 94 closed. To open the grippers, it is necessary to urge the crank arms apart, and a cam arrangement is provided for this purpose. This includes rollers 102 supported on the side of the longer arms 100, and a cam 103 rotatably mounted on shaft 98, and having a properly formed periphery for cooperating with the rollers 102. In the position shown in Fig. 11, the cam 103 permits the grippers 94 to be in the engaging position, whereas rotation of this cam in either direction will cause the rollers 102 to ride on higher parts of the cam surface and to separate. The rotation of cam 103 is effected by the aid of arms 104 and 105, which are adapted to engage projections in the path of movement of the arms as the grippers 94 are moved. Once the cam 103 is rotated to a definite position, enough friction is present on its surfaces to retain it in that position until one or the other of the arms 104, 105 is engaged. Thus for opening the grippers, there is provided a stationary cam or projection 106 (Figs. 4 and 11) fastened to one of the side frames 23 and in the path of movement of the arm 104. The other arm 105 is used to close the grippers, when they are in proper position to receive the sheet 34 from the powdering mechanism.

For the purpose of moving these grippers bodily so that they may receive the sheet as just stated, carry it to the shaker device, and finally deliver it to the heater, a link 107 is provided at one end of shaft 98, as 130

shown in Fig. 1. This link carries a roller 109 engaging in a slot or groove 108 formed in frame 23 and serving as a guide therefor. The link 107 is rigidly attached at one end 5 to the projecting end of shaft 98. A clevis 110 also passes over shaft 98 and serves as a bearing therefor. Another roller 109 is rotatably mounted on this shaft behind this clevis, and is likewise guided for movement 10 in the groove 108. It is evident that by moving the clevis 110 along the groove 108, the grippers will be correspondingly moved. On the other end of the shaft 98 there is 15 no link corresponding to link 107, since but one is necessary to keep the angular relation of the shaft to the groove correct.

The mechanism for providing this movement and for synchronizing it so as to have the grippers 94 meet the sheet 34 in the position of Fig. 14, is best illustrated in Fig. 1. The gear 57 which serves as one of the train that drives the powdering mechanism shaft 49, is provided with a pitman 112 that is connected to the short arm of a lever 113. 20 This lever is rigidly fastened to a shaft 114 that extends across the machine and is journaled in the side frames 23. A lever 115 similar to lever 113 is attached to the other end of the shaft 114, as shown in Fig. 2; but 25 of course the pitman 112 is directly connected only to the lever 113. A counterweight 116 is also fastened to the levers 113 and 115, as by the aid of a rod 117 located between them. This counterweight serves to balance 30 the levers, whereby the operation is rendered less energy-consuming, and generally smoother. The longer arm of the levers 113 and 115 has a longitudinal guideway 118, in which a rod 119 is accommodated. This rod 40 is connected to the corresponding clevis 110. the telescoping arrangement between rods 119 and the levers 113 and 115 provide for a variation in the effective length of the lever arm as the link 107 and rollers 109 45 are moved in the slot 108, which is non-circular. Instead this slot has a substantially horizontal portion and a steep portion passing parallel to and over the steep wall 65 of the powder trough 63.

50 The angular relation of the pitman 112 with respect to the powdering mechanism shaft 49 is such that the grippers 94 approach the extreme lower point of their travel (as illustrated in Fig. 14), just as 55 the sheet 34 is released by the fingers 67, so that these grippers may take hold of the paper. As shown most clearly in Fig. 4, the grippers 94 are so arranged along the supporting shaft that they may dovetail with 60 the fingers 67, whereby no interference can result in the position of Fig. 14. Furthermore, the slotted bottom of the clamping bar 66 permits the insertion of the upper fingers of the grippers 94 under the edge of 65 sheet 34. Of course the grippers 94 are open

until this insertion takes place, and immediately afterwards, they are closed and are moved upwardly and away from the bar 66.

The mechanism for closing the grippers 94 at this point is shown most clearly in Figs. 3 and 7. A stop or projection 120 is arranged to be projected into the path of movement of the closing arm 105 (Fig. 11) of the grippers, whereby the cam 103 will be rotated to the closing position. This projection is properly located to act at the desired point of travel of the grippers, and in the arrangement disclosed, it is made to project through a slot in the wall 65, and is retracted after it accomplishes its function, so as not to interfere with the movement of the sheet 34. In order to project this member 120 at the proper time, it is mounted on a shaft 121, journaled in one of the side frames 23. Fastened to the shaft is a forked lever 122, forming in fact, a mutilated gear of only two teeth. This lever is urged to a position where projection 120 is retracted, by a tension spring 123, and a stop 124 insures against undue retraction. In order to rock 90 this lever so as to project the member 120 outwardly, a dog or cam 124 is used, supported for rotation with the main shaft 49, as by fastening it to a disc 125. This dog 95 operates on lever 122 through the intermediary pivoted lever 126, which has teeth co-acting with the forked end of lever 122, and a projection at the other end in the path of travel of dog 124. The projection 120 is 100 projected only for a very short period, corresponding to the period of engagement between dog 124 and lever 126, for as soon as this dog clears the lever, spring 123 is allowed to return the parts to the position of Fig. 3. The dog 124 is very accurately 105 placed with respect to the angular position of the powdering mechanism and of the pitman 112 so that the gripping operation is performed at the proper point.

As soon as the sheet 34 is gripped in the 11 manner just described, it is carried upwardly near the steep wall 65, and much of the loose powder drops back into the trough 63. Fig. 10 shows diagrammatically this stage 115 in the operation of the machine. The interchange of the sheet 34 from the powdering mechanism to the grippers 94 is of great importance, so as to insure against the carrying of any powder on the mechanism that holds the sheet. This result is also facilitated by 12 the provision of beaters or hammers 127 which operate on the back of the sheet while it is moved by the grippers 94 over the steep wall 65. These hammers vibrate the sheet 125 strongly enough to remove from it substantially all of the powder that is not stuck to the wet printing. An important feature 130 of the invention is the use of centrifugal force for urging the hammers 127 against the sheet. In this way, yielding blows only 135

are delivered, and the danger of tearing or otherwise injuring the paper is obviated.

To accomplish this result, each of the hammers 127 is mounted on its associated crank arm 128, there being in the present instance four hammers and four crank arms. These arms are fastened on a shaft 129, and are spaced apart thereon. They are also displaced angularly from each other by 90° as indicated most clearly in Figs. 8, 9 and 10. The hammers 127 may be made to project through slots 130 (Fig. 4) provided in the wall 65, so as to impinge against the sheet 34 as it moves past the slot. By rotating shaft 129, centrifugal forces will act on the hammers tending to make them radial, and these forces thus serve to urge the hammers yieldingly against the sheet 34. The angular displacement of the hammers and the use of centrifugal force are of material assistance in bringing the sheet into very rapid vibrations of small amplitude, which is so desirable to free the sheet of the surplus powder.

The rotation of shaft 129 is accomplished by the aid of a pulley 131 (Fig. 7) fastened thereto, a belt 132, and a drive pulley 133 mounted on a driven shaft 134. This shaft, which is journaled in one of the side frames 23, is driven by the aid of the sprocket pinion 53 shown in Fig. 1, deriving its power from chain 51 and the drive shaft 26. The gear ratios are such that the proper high rate of rotation of the hammers 127 is secured. The shaft 129 is journaled in a fork 135, and this fork in turn is so arranged that the whole hammer mechanism can be shifted toward and from the back of sheet 34. This shifting is useful for several purposes, such as for the retraction of the hammers out of the path of the grippers 94, and also for regulating the force with which the hammers are permitted to strike the sheet. The fork 135 is accordingly pivoted on a shaft 136, and a spring 137 operating on an arm 138 of the fork tends to move the hammers toward the sheet. It is however prevented from doing so except when this is desired, by the aid of the mechanism disclosed most clearly in Figs. 2 and 3. To the shaft 136 that carries the fork 135, there is attached a lever 138 having a surface 139 arranged to coact with a cam surface 140 on the disc 125. This disc rotates with shaft 49, and for the greater portion of its periphery, it holds lever 138 up and thus prevents spring 137 from moving the hammer mechanism outward. However, at a point corresponding to the arrival of the grippers 94 a little beyond slots 130, the lever 138 is gradually allowed to drop by following cam surface 140, and finally reaches the lowest point 141. The hammers 127, which are controlled by the arm or lever 138, are thus rendered active. As the sheet 34 is moved across the

slots 130, the hammers are gradually projected farther and farther through these slots, by the aid of the gradually sloping cam surface 139, and their force of impact is correspondingly increased. This increase in the action of the hammers is of benefit, so as to influence the sheet with a correspondingly large force near its free edge; due to the fact that the lower edge of sheet 34 is unsupported, and violent vibration or beating near this edge is necessary to produce sufficient vibration of the sheet 34 in order to counteract its yielding effect, at that stage. A sheet metal cover 165 may if desired be provided for the hammer mechanism.

In order to assist in the operation of the beaters to a large extent, and also to prevent the sheet from being thrown out violently by the hammers during this later stage of operation, I prefer to use a plurality of spring fingers 142 that are moved automatically toward the unattached, bottom edge of the sheet 34 as it moves past. For this purpose these fingers are attached to a transverse shaft 143 that is journaled in ears 144 on frames 23. A spring 145 (Figs. 1 and 4) is arranged to urge the fingers 142 normally toward the wall 65 by the aid of a crank arm 146. In order to keep these fingers clear while the grippers 94 are moving toward the powdering mechanism, as well as while moving away from them until such movement brings the grippers well away from under these fingers, I provide another crank arm 147 (Fig. 1) carrying a long projection or dog 148 extending past the slot 108. Now as the link 107 moves down this slot, this dog 148 is engaged by the gripper moving mechanism, and the fingers 142 are raised out of the way. Since the dog 148 is quite long, it will remain in engagement with this mechanism for the remainder of the forward movement of the grippers, and will not become free again until it is desired to permit the fingers to come down on the sheet 34. The provision of fingers 142 is of the greatest importance, for without them the powder could not be well shaken off. The fingers permit the sheet 34 to yield only enough to prevent its rupturing, while hammers 127 are free to exert considerable force against it.

The grippers 94 in their continued movement, finally carry the sheet 34 entirely past the beaters or hammers 127, and over the horizontal conveyor belts 149. These belts are disposed on shafts 150 and 151 journaled in the frames 23. The shaft 151 carries a sprocket wheel 152 which is driven by a chain 153 and driving wheel 154. The conveyor belts 149 finally receive the sheet 34 in a manner to be hereinafter described, and convey it to the heater. The drive mechanism for this conveyor arrangement

is such that its speed may be varied, so that when long sheets are carried thereby, it may have ample time to carry each of them away from under the succeeding sheet. This variable speed drive includes the shaft 155 on which the sprocket wheel 154 is mounted. As shown most clearly in Fig. 2, this shaft at its other extremity carries a gear 156 which may be placed selectively into operative connection with any one of a plurality of varying sized gears 157, 158 and 159. All of these gears are fastened to the shaft 49. When large gear 157 is active, the shaft 155 is rotated fastest, and when the smaller gears are active, progressively slower speeds are obtained. The change from one gear to another is accomplished for example by the aid of a manually operated lever 159^a pivoted on shaft 160 and axially movable thereon. The lever 159^a carries two idler pinions 161 and 162 which are constantly in mesh. One of these gears, such as 162, is rotatably mounted on shaft 160, and is in mesh constantly with the pinion 156. The other pinion is rotatably mounted on a short stub shaft 163 carried by lever 159^a. By proper rotation and sliding of lever 159^a on shaft 160, it is possible to cause pinion 161 to engage any one of the driving gears 157, 158, and 159. The face of pinion 156 is made wide enough to take care of the axial movement of the pinions 161 and 162, and to maintain pinion 162 continually in mesh with it.

35 The grippers 94 continue to move toward the rear, due to the movement of pitman 112, and near the extremity of their movement, they are opened by the striking of arm 104 against the stationary plate 106, as hereinbefore described. The sheet 34 may now drop down on the conveyor belts 149. In order to facilitate the disengagement of the sheet from the grippers, I provide a plurality of pusher fingers 164 which are arranged to be engaged by the edge of sheet 34 just as the grippers 94 open. These fingers dovetail between the grippers 94, as shown in Fig. 4, and are furthermore so arranged that they permit the shafts 95, 96 and 98 supporting the grippers to pass under them, but soon thereafter they are moved downwardly in the path of travel of the sheet 34. For this purpose, the fingers 164 are fastened to a transverse shaft 166, rotatably supported in the brackets 167 fastened to the side frames 23. Near one end of the shaft, a crank arm or dog 168 is fastened, for operating the shaft. As shown in Fig. 4, this arm is placed just inside the frame 23 and in the path of movement of shaft 98. This shaft is arranged to move arm 168 just as the grippers 94 open, whereby fingers 164 are moved downwardly against the action of a spring 169, fastened to another crank arm 170, carried by shaft 166. The

sheet 34 is by the mechanism just described, pushed out of the gripper jaws and onto the conveyor belts 149. Beneath these belts a sheet metal plate 171 is provided, for keeping the lower reaches covered, and for supporting the upper reaches in a horizontal position. Soon after the sheet is thus released, the grippers 94 start their return travel toward the powdering mechanism, to grip a succeeding sheet. This condition is illustrated in Fig. 9.

The conveyor belts 149 carry the sheet 34 onto another conveyor 172 which is adjacent thereto. This conveyor is driven from the conveyor shaft 151 by the aid of sprocket wheel 173 and chain 174, driving the conveyor shaft 175. This shaft is connected with the other conveyor shaft 176 by another chain 177. The conveyor 172 is formed of heat-resistant material, such as woven wire, so that it may conduct the sheet 34 through the heater 178. A support 179 is also provided for the upper reach of this conveyor.

The heater 178 is arranged to operate above the sheet 34, so as to radiate heat to the top surface thereof. It consists of a hollow reflecting shell, disposed over the conveyor 172, and lined throughout with some heat resistant material 179^a. In the present instance the source of heat is shown as a pair of electrical heating elements 180 that are appropriately supported on one side of the hollow shell. In order to regulate the degree of heat affecting sheet 34, I arrange the heater so that it is bodily movable toward and from the conveyor 172. For this purpose the entire shell is supported on pivots 181 located in the frames 23, and its sides has depending portions 182 that pass between the belt 172 and these frames. Adjustment of the heater 178 is secured by the aid of a hinged bolt 183 carried on top of the heater 178, and passing through a stationary strap 184. A hand nut 185 engages the bolt and rests on top of the strap 184, whereby rotation of this nut serves to raise and lower the heater 178. Adjustability is not only desirable but essential in order to take care of varying conditions, such as quality of paper to prevent scorching, amount of printing thereon, and speed of the conveyor 172. All of the factors are of course so regulated that fusion of the powder and subsequent thorough drying are secured.

After the conveyor 172 carries the sheet through the heater 178, it delivers the sheet to a delivery conveyor 186, which is entirely similar to the conveyor 172. As shown in Fig. 1, this conveyor is mechanically connected, as by chain 187, with the conveyor 172 and is thus driven thereby. Both conveyors 172 and 186 are supported in a collapsible extension 188 of the frames 23,

hinged on shaft 150 and held in horizontal, operative position by a pair of struts 189. When struts 189 are removed from cooperation with the frame 21, the frame extensions 188 are permitted to drop down, and the entire machine can be shipped or stored in a relatively small space.

The description of the machine is now complete. It is perhaps helpful at this point to summarize the operation. Assuming that motor 22 is running, and that the gear ratio and heating device 178 are properly adjusted to give the desired results, a sheet 34 just off the press is delivered to feeder conveyor 24 (Fig. 8). This conveyor carries it to the projections 43. As soon as shaft 49 rotates sufficiently, cam 48 causes the sheet to be released from projections 43, and to pass onto the plate 35, where fingers 36 keep it in spaced position. As soon as cam 48 becomes inactive, the sheet is gripped by the powdering mechanism between bar 66 and fingers 67. The sheet is carried around to the position of Fig. 14 by this means. In the meanwhile, the scoop 62 has dipped into the powder 64 and has deposited it on the trough 79, whence it is poured onto the sheet 34, some of it adhering to the tacky printing. The grippers 94 are now in proper position to receive the sheet, and are automatically closed at the instant fingers 67 are released. The grippers 94 carry the sheet 34 past the rapidly rotating beaters or hammers 127, which gradually increase their force as the sheet 34 travels past them. At the same time fingers 142 come into play to confine the sheet 34 against undue movement in response to the beating action, and also to permit the hammers to act with full force on the sheet. At this stage, all surplus powder falls back into the trough 63. The grippers 94 continue their movement, and finally deposit the sheet onto the movable conveyor 149, being assisted by the fingers 164 to free the sheet from the jaws of the grippers. These grippers are of course first opened by operation of cam 183. The conveyor 149 feeds the sheet to the conveyor 172, which carries it underneath the electrical heating elements 180, whereby the powder is fused and dried. Finally the conveyor 172 delivers the completed sheet to the delivery conveyor 186.

55 I claim:

1. In a machine of the class described, means for applying a powder to the matter to be treated, and gripping means for carrying the matter away from the powdering mechanism and engaging the matter only on completion of the powdering operation.

2. In a machine of the class described, a powdering mechanism for a sheet to be treated, said mechanism having a clamping

means for said sheet, and means for delivering said sheet to the clamping means, comprising a removable stop for the sheet, a plate upon which the sheet is arranged to rest when the stop is removed, means for positioning the sheet with respect to the plate, and a common means operative in response to the operation of the powdering mechanism, for removing the stop and for operating the positioning means.

3. In a machine of the class described, a powdering mechanism for a sheet to be treated, said mechanism having a clamping means for said sheet, and means for delivering said sheet to the clamping means, comprising a removable stop for the sheet, a plate upon which the sheet is arranged to rest when the stop is removed, means for positioning the sheet with respect to the plate, and a cam carried by the powdering mechanism, for causing the stop to be removed and the positioning means to be operated.

4. In a machine of the class described, a powdering mechanism, comprising a scoop movable to pick up powder and to dump it, a mechanism for driving the scoop, clamping means for a sheet to be powdered, movable as the scoop is operated, and means for releasing said clamping means as soon as the powdering operation is completed.

5. In a machine of the class described, a powdering mechanism, comprising a scoop movable to pick up powder and to dump it, means for revolving the scoop so that it performs these functions in succession during a revolution, clamping means for a sheet to be powdered and means for releasing said clamping means as soon as the powdering operation is completed.

6. In a machine of the class described, a powdering mechanism, comprising a scoop revoluble to pick up powder and to dump it, a rotatable support for said scoop whereby the scoop is hingedly carried thereby on an axis displaced from the axis of rotation of the support, and means for supporting a sheet to be powdered in operative position with respect to said scoop.

7. In a machine of the class described, a powdering mechanism, comprising a scoop revoluble to pick up powder and to dump it, a rotatable support for said scoop whereby the scoop is hingedly carried thereby on an axis displaced from the axis of rotation of the support, means for controlling the extent of rotation of the scoop about its own axis, and means for supporting a sheet to be powdered in operative relation with respect to said scoop.

8. In a machine of the class described, a powdering mechanism, comprising a scoop revoluble to pick up powder and to dump it, a rotatable support for said scoop whereby

the scoop is hingdly carried thereby on an axis displaced from the axis of rotation of the support, a cam for controlling the extent of rotation of the scoop about its own axis, 5 and means for supporting a sheet to be powdered in operative relation with respect to said scoop.

9. In a machine of the class described, a mechanism for dumping powder on a sheet 10 to be treated, clamping means for the sheet, said mechanism shielding the clamping means from the powder.

10. In a machine of the class described, a mechanism for powdering a sheet, clamping 15 means for the sheet, said mechanism comprising a trough arranged to shield the clamping means to prevent the powder from pouring thereon, and means for moving said trough into operative position after the sheet 20 is clamped.

11. In a machine of the class described, a movable scoop for dumping powder on a sheet to be treated, clamping means for the sheet for holding it in proper operative position 25 with respect to the scoop, and a trough movable to be positioned over the clamping means for guiding the powder over the sheet.

12. In a machine of the class described, a movable scoop for dumping powder on a sheet 30 to be treated, clamping means for the sheet for holding it in proper operative position with respect to the scoop, a support for the scoop, a trough pivotally mounted on said support, and means for moving said trough 35 on its pivot so that it covers the clamping means and guides the powder over the sheet.

13. In a machine of the class described, a rotatable frame, clamping means carried by the frame for holding a sheet to be treated, 40 and a scoop also mounted on the frame.

14. In a machine of the class described, a rotatable frame, clamping means carried by the frame for holding a sheet to be treated, a scoop pivotally mounted on a center 45 offset from the axis of the frame, and means for controlling the movement of the scoop about its own axis.

15. In a machine of the class described, a rotatable frame, clamping means carried 50 by the frame for holding a sheet to be treated, a scoop mounted on the frame, and a trough carried by the frame and cooperating with the scoop.

16. In a machine of the class described, 55 a rotatable frame, clamping means carried by the frame for holding a sheet to be treated, a pivotal support on said frame having its pivotal axis displaced from that of rotation of the frame, and a scoop pivoted 60 thereon.

17. In a machine of the class described, 65 a rotatable frame, clamping means carried by the frame for holding a sheet to be treated, a pivotal support on said frame having its pivotal axis displaced from that of rota-

tion of the frame, a scoop pivoted thereon, and a trough also pivotally carried thereon, said trough cooperating with the scoop and covering the clamping means.

18. In a machine of the class described, 70 means for powdering a sheet, and means for agitating the sheet so as to free it from surplus powder, comprising a rotatable element having beaters pivoted thereon and movable outwardly from the axis of rotation under the influence of centrifugal force. 75

19. In a machine of the class described, means for powdering a sheet, and means for agitating the sheet so as to free it from surplus powder, comprising a beater arm 80 mounted for rotation near one end, and means for revolving said arm so as to cause centrifugal force to move said arm about its axis.

20. In a machine of the class described, 85 means for powdering a sheet, means for agitating the sheet so as to free it from surplus powder, means for carrying the sheet past said agitating means so that parts of the paper in succession will be acted on by 90 the said agitating means, and means for controlling the intensity of the agitations in accordance with the relative position of the sheet with respect to the agitator.

21. In a machine of the class described, 95 means for powdering a sheet, an agitator for engaging the sheet so as to free it from surplus powder, and a movable support for the agitator, whereby the intensity of the agitation may be adjusted by moving the support toward and from the sheet. 100

22. In a machine of the class described, means for powdering a sheet, an agitator for engaging the sheet so as to free it from surplus powder, a movable support for the 105 agitator, means for moving the sheet past the agitator, and means for moving the support in response to the movement of the sheet past the agitator.

23. In a machine of the class described, 110 means for powdering a sheet, an agitator for engaging the sheet so as to free it from surplus powder, a pivotally mounted support for the agitator, and a cam for moving the support on its pivot so as to vary 115 the intensity of the agitation.

24. In a machine of the class described, means for powdering a sheet, and means for agitating said sheet, comprising a rotatable shaft, and a plurality of arms supported on said shaft and pivoted so as to permit them to extend outwardly from the shaft due to centrifugal force, said arms being displaced axially and angularly with respect to each other. 120

25. In a machine of the class described, 125 means for powdering a sheet, means for agitating the sheet, means clamping the sheet near one edge and carrying it past the agitating means, and means for engag- 130

ing the sheet for preventing undue displacement or movement thereof in response to the action of the agitating means.

26. In a machine of the class described, means for powdering a sheet, means for agitating said sheet, a gripper engaging said sheet near one edge thereof, means for moving the gripper so as to carry the sheet past

the agitating means, and movable means arranged to be moved in contact with the sheet for limiting its movement in response to the operation of the agitating means.

In testimony whereof, I have hereunto set my hand.

RICHARD F. BERNDT.
